CLAIM

The ornamental design for a pet harness, as shown and described.

DESCRIPTION

FIG. 1 is a top, front, right perspective view of a pet harness, showing my new design;

FIG. 2 is a top, rear, left perspective view thereof;

FIG. 3 is a front elevational view thereof;

FIG. 4 is a rear elevational view thereof.

FIG. 5 is a left side elevational view thereof;

FIG. 6 is a right side elevational view thereof;

FIG. 7 is a top plan view thereof;

FIG. 8 is a bottom plan view thereof;

FIG. 9 is a right side elevation view of the pet harness of FIG. 1 shown in an alternate configuration for use; and,

FIG. 10 is a top, rear, right perspective view of the pet harness of FIG. 1 shown in condition for use upon a dog. The broken lines immediately adjacent to the shaded, claimed portions of the pet harness define the boundaries of the design. All other broken lines shown on the remainder of the pet harness depict unclaimed subject matter and form no part of the claim. Additionally, the broken line showing a dog in FIG. 10 depicts environmental subject matter only and forms no part of the claimed design. All broken lines form no part of the claimed design.
